UNITED STATES PATENT OFFICE.

BERNHARD C. J. ANDERSON, OF CHICAGO, ILLINOIS.

MACHINE FOR ORNAMENTING STRIPS OF COMPOSITION OR FOR COATING MOLDINGS THEREWITH.

SPECIFICATION forming part of Letters Patent No. 443,421, dated December 23, 1890.

Application filed April 16, 1890. Serial No. 348,250. (No model.)

To all whom it may concern:

Be it known that I, BERNHARD C. J. ANDERSON, a citizen of the United States, residing in Chicago, in the county of Cook and 5 State of Illinois, have invented certain new and useful Improvements in Machines for Ornamenting Strips of Composition or for Coating Moldings Therewith, of which the following is a specification.

10 The present invention relates, generally, to machines for ornamenting strips of composition by pressing them while still plastic into any desired shape and impressing their surfaces with any desired design or configuration by passing them between rolls whose peripheries are so designed as to produce the desired effect. The said invention relates more especially to those machines which, in the operation of shaping and ornamenting 15 the plastic composition, at the same time 20 press it firmly upon strips of molding.

The object of the invention is to provide a machine having a work-support, which may be placed horizontally or inclined to any desired angle within a radius of nearly ninety 25 degrees above the horizon.

The invention consists in certain novel features and combinations that are particularly pointed out in the claims hereinafter, 30 a machine embodying said invention being first fully described with reference to the accompanying drawings, which form a part of this specification, and of which—

Figure 1 is a front elevation of said machine viewed in the direction indicated by the arrow 1, Fig. 2. Fig. 2 is a side elevation thereof viewed in the direction indicated by the arrow 2, Fig. 1. Fig. 3 is a side elevation of a portion thereof viewed in the 35 direction indicated by the arrow 3, Fig. 1. Fig. 4 is a plan view of the pedestal and the parts situated beneath the plane of its top, the pedestal itself and the work-supporting roll being shown partly in section. Fig. 5 is a front elevation of the machine with the 40 work-support inclined and the other parts adjusted to corresponding positions. Fig. 6 is a horizontal section on the line 66, Fig. 2, showing in plan only some of the parts below 45 the cutting plane. Figs. 7 and 8 are respectively a side and a front elevation of the vertically-movable frame. Fig. 9 is a vertical sec-

tion of the atomizer. Fig. 10 is a plan view thereof. Fig. 11 is an elevation showing in detail certain parts hereinafter more fully 55 described. Fig. 12 is an elevation of the rotary cutters and their accessories.

The base or pedestal 1 preferably consists of a single hollow casting of substantially square shape in cross-section, having on top 60 a pair of heavy horizontal flanges or rails 2 and 3, which are parallel to each other and situated at the front and back, respectively, of the pedestal. Extending from one of these rails to the other at about the center of the 65 pedestal is a heavy rib or rail 4, and from this rib a web 5 extends to and slightly beyond the side 6. Upon the other side of this rib 4 the top of the pedestal is entirely open between the flanges 2 and 3, and the side 7 70 has a large opening 8, of truncated V shape, extending more than half-way to the bottom, for a purpose that will appear presently.

10 is a heavy arm projecting from the side 6 and curved so as to extend rearward beyond the rear side 11 of the pedestal. At its extremity, cast integrally with it, are two halves of two two-part journal-boxes 12 and 13, situated one above the other, with their axes horizontal. Projecting from the rear 80 wall 11 is a second arm 14, having at its extremity two halves of two two-part journal-boxes 15 and 16, situated one above the other and with their axes coincident with the axes of the boxes 12 and 13, respectively. 85

At top the side 7 of the pedestal is formed with two halves of two two-part journal-boxes 17 and 18, situated, respectively, at the front and rear of the pedestal and with their axes horizontal and coincident. Journaled in the 90 boxes 12 and 13 is the main shaft 19, upon which is a fast pulley 20 and a loose pulley 21. The belt-shifter consists of two curved parallel arms 22, secured at proper distance apart to a slide-rod 23, which passes loosely 95 through an eye formed through the extremity of an arm 24, projecting from arm 10, and through an eye formed through the side 6 of the pedestal, its inner end being connected by a hinge-joint to the upper extremity of a 100 long arm 25, whose lower extremity is rigidly connected to the inner end of a rock-shaft 26, to the outer end of which is secured the operating-lever 27. Upon the shaft 19 is a small

pinion 28, which gears with a larger wheel 29, fixed to a shaft 30, that is journaled in boxes 13 and 16 and carries at its extremity a beveled pinion 31.

32 is a yoke, which has upon its opposite sides trunnions 33 and 34, journaled in the boxes 17 and 18 already described. One of these journals 34 is hollow, and within it is journaled a shaft 35, to one end of which is fixed a beveled pinion 36, which gears with pinion 31, and to the other end of which is fixed a beveled pinion 37, contained within an enlarged cavity in the yoke. The yoke is provided on its outer side with a large boss 38. This boss and the inner portion of the yoke are provided with circular bores, in which a shaft 39 is journaled. To this shaft within the central opening of the yoke is secured a beveled pinion 40, which gears with pinion 37, and to the extremity of said shaft that projects beyond the boss 38 is secured a roll 41. The projecting extremity of shaft 39 is reduced, so as to form a shoulder 42, which engages the roll 41 and holds it out of contact with the extremity of the boss 38. The inner end of the roll is hollowed out, so as to receive within it and project well over the boss 38. Its outer end is also hollowed out to receive and in- close the nut by which it is held to its shaft. At its inner end it has a short radial flange 43, which serves as a guide and support for a removable annular support 44. (Shown in Fig. 5.) This support preferably consists of a radial flange of the desired width formed upon a ring or collar 44^a, which fits the roll 41. It is also preferably split and provided on its abutting ends with corresponding perforated lugs for the reception of screw-bolts, whereby it may be adjusted to any position on the roll and there firmly clamped. In Fig. 5 of the drawings it is shown resting against the flange 43, and an additional ring 45 is slipped up against it, the latter forming the direct support for the work, while in Fig. 11 it is shown clamped to the roll some distance from the flange 43. When the roll 41 is used in horizontal position, as shown in Figs. 1 to 4, inclusive, two of these rings 45 may be employed for guiding the work, in which case they are secured to the roll by screws, as above described, at such distance apart that the strip of work passes easily between them and rests upon the roll.

55 Fixed to the projecting extremity of the journal 33 of the yoke is a collar 46, from the top of which rises a perforated lug 47, in which is fixed one end of a stud 48 a little longer than the roll 41 and extending outward parallel therewith, the top side of said stud being a trifle lower than the top side of the roll. Upon this stud are adjustable guide-rings 49, having set-screws for holding them in place. Upon the other side of roll 41 is a stud 50, similar to stud 48.

51 is a segment upon the under side of the yoke, the periphery of which projects be-

tween a pair of clamping-jaws 52 and 53. A screw-threaded shaft 54, having upon it a shoulder or collar 55, passes loosely through a perforation through the jaw 53 and is tapped into jaw 52. By turning the shaft by means of a hand-wheel 56 the jaws may be allowed to spring apart, or they may be forced together, causing them to clamp the segment 51. Resting upon the top of the pedestal is a horizontally-movable frame comprising the parts numbered 60 to 65, inclusive.

60 and 61 are a pair of plates of inverted-U shape, (approximately,) the rear standards 60^a of which are vertical. 62 is a web connecting them at front and top.

63 is a heavy flange connecting the lower ends of the front standard 60. 64 is a similar flange connecting the lower extremities of the rear standards 60^a. The flanges 63 and 64 are parallel and the same distance apart as are the rails 2 and 3 of the pedestal upon which they rest. Each of the rails 2 and 3 is provided with a groove 57, and each of the flanges 63 and 64 is provided with a rib 58, which ribs enter the grooves for preventing said flanges from moving laterally with respect to said rails while permitting them to slide upon them in the direction of their length. The rails 2 and 3 are provided, also, with holes 59, in which are tapped screw-bolts 66, which pass through longitudinal slots in flanges 63 and 64, and enable the movable frame to be secured to the pedestal after it has been brought to the desired position thereon. The part 65 is a plate or web, which joins the inside vertical edges of the rear standards 60^a and projects at its edges slightly beyond them, forming tongues 67 and 67^a, which are beveled off on their rear sides. These tongues constitute vertical guides for the vertically-movable frame shown in Figs. 7 and 8.

68 is a plate, from the uppermargin of which projects forward a horizontal strengthening-flange 69. From its side margins project forward a pair of vertical flanges 70 and 71, which carry at their lower margins the upper halves of two two-part journal-boxes 72 and 73, respectively. From its side margins also project rearward a pair of flanges 74 and 75, the former of which is straight, while the latter has an under cut groove which receives and fits the vertical guide 67^a. Between the flange 74 and the guide 67 is placed a clamp-plate 76, one side of which is straight and fits the straight inner side of flange 74, while the other side is beveled and fits the inclined rear side of guide 67. Tapped into this clamp-plate is a screw 77, which passes through a perforation formed through plate 68, and is provided with a shoulder, which bears against the front face of said plate, and a handle 78, whereby it is turned.

79 is a perforated lug cast upon the front side of plate 68, in which is swiveled the lower extremity of a screw 80, which passes through perforations through the top portion of web

62 and through a circular boss 81 cast thereon. 82 is a nut turned onto the screw and bearing upon the boss 81, and 83 is a hand-wheel fixed to or formed with said nut, whereby it 5 may be turned for elevating or lowering the screw.

Journalized in boxes 72 and 73 is a shaft 84, situated in the same vertical plane as shaft 42 and projecting beyond the side of the 10 frame of the machine about as far as does the roll 41. Upon the projecting end of this shaft a cylinder or roll 85, hereinafter called the "pattern-roll," is fixed so that it will turn with the shaft 84, and may be adjusted thereon or 15 removed therefrom and replaced by another. The periphery of this roll has contact with the plastic composition and shapes and ornaments it, and if the strip of composition be laid upon the top of a strip of molding and 20 both be passed through the machine together at the same time that the composition is shaped and ornamented it will be firmly pressed upon the molding. Upon the other end of shaft 84 is a pinion 86, which gears 25 with a larger wheel 87, and the latter in turn gears with a small pinion 88, fixed upon the shaft 30 by means of a spline and groove, so as to be capable of sliding longitudinally thereon. The pinion 88 has an elongated hub 30 89, terminating in a flange 90. This hub occupies an eye formed at the lower end of a lever 91, which is provided near its upper end with a second eye, through which passes the shaft 92, upon which wheel 87 is journaled. 35 This shaft also passes through an arcuate slot 93, formed concentrically with shaft 30 through an arm 94, projecting rearward from the horizontally-movable frame. The lever 91 and arm 94 occupy a portion of the shaft 40 40 between a flange 95 and a nut 96, by tightening which latter the parts may be secured in any position to which they may be adjusted. It will be seen that by moving this wheel 87 in a path concentric with the wheel from 45 which it derives its motion, 88, the connection is not broken, and whatever may be the elevation of wheel 86 wheel 87 may be brought in gear with it, thereby enabling the latter to be adjusted vertically, as required. It will 50 be seen, also, that the spline-and-groove connection between shaft 30 and pinion 88 enables the superposed frame 60, &c., to be slid upon the rails 2 and 3, carrying with it its attached parts without breaking the connection 55 between the source of power and the working parts.

97 is an arm having a longitudinal slot, through which passes a bolt by which it is secured adjustably to the outside of flange 71. 60 To the extremity of this arm is secured rigidly a stud 98, which projects outward about as far as does the shaft 84. Upon this stud is a pair of adjustable collars 99, held in place by set-screws, and to each of these collars is 65 fixed a rigid arm 100. To the extremity of each of these arms is secured by a set-screw 101 a guide-plate 102, said plates being slot-

ted for the passage of said screws, so as to permit said plates to be adjusted for the purpose that will appear presently. 70

103 is a heavy lug projecting from the side 7 of the pedestal just above box 18 and extending into the V-shaped opening 8. To this lug is fixed one end of a horizontal stud 104, which projects outward parallel with the 75 supporting-roll and a little beyond it, the top side of said stud being slightly below the level of the top side of said roll. This stud is incapable of rotating, and from it a pair of rigid arms 105 (one near each of its ends) project 80 rearward and upward. Between these arms the stud is inclosed in a loose sleeve 106, which serves as an anti-friction roller. To the extremity of each of these arms 105 is hinged one end of a link 107, the other ends of said 85 links being connected rigidly to the respective ends of a short shaft 108, which they hold against rotation.

Surrounding the shaft 108 is a loose sleeve 109, to which are adjustably secured by set-screws any desired number of rotary cutters 90 110, whose peripheries rest when not at work upon the sleeve 106, against which they are pressed with the necessary force by a pair of tension-springs 111, each connected at one 95 end to one of the arms 105 and at the other end to the corresponding link 107.

112 is an air-pump, the piston-rod 113 of which is connected by a pitman 114 to a wrist-pin 115, secured eccentrically to the end of 100 shaft 19.

116 is a short stout arm secured to the bottom portion of the vertically-movable frame, and having upon its opposite sides a pair of bosses or short studs situated opposite each 105 other and provided with communicating bores. Over one of these perforated bosses is slipped one end of a section of rubber tubing 117, the other end of which is connected with the pump. Upon the other of these bosses is 110 screwed one end of a jointed bracket 118, (similar to a wall-bracket for gas,) which may have any desired number of joints. The free end of this bracket carries a cup 119 and its bore communicates with a bore 120, that discharges horizontally over and in close proximity to a vertical bore or duct 121, which communicates with the bottom part of the cup. These parts form an atomizer of such well-known form that further description is not 115 necessary. This atomizer is for the purpose of keeping the surface of the pattern-roller wet, and this it does more uniformly than can possibly be done with a sponge, as it throws the fine spray well into every crevice 120 of the pattern-roll. The jointed bracket enables it to be placed directly opposite the pattern-roll and at any desired distance therefrom. For regulating the area of the spray the cup is provided with three curved sheet-metal shields, which may easily be adjusted with relation to each other. Two of these shields 122 are curved to fit the interior of the rim of the cup, and are held upright by springs 130

123, which are secured to their outer sides and project downward over the rim of the cup, bearing against its outsides. These shields may be slid around the rim of the cup, so as to 5 leave between their adjacent edges, directly opposite the bore 120, an opening of any desired width. The third shield 124 is curved to fit the interior of the shields 122, and has two springs 125, which are presented in opposite 10 directions and embrace the adjacent edges of said shields 122. These springs 125 do not interfere with the above-described adjustment of shields 122, and at the same time they permit the shield 124 to be raised or lowered, so as to leave any desired space between 15 its lower edge and the top of the cup. The bracket is provided with a three-way cock 126, by which the air may be cut off from the atomizer and discharged through a hole 127.

20 Assuming the parts to be as shown in Figs. 1 to 5, inclusive, the operation is as follows: A strip of the plastic composition of a width a little less than the distance between the guide-rings 49 is placed on top of a strip 25 of sheet-zinc of the same width. They are then rested on the stud 48 between guide-rings 49 and their ends passed between guides 102 and inserted between the roll 41 and the pattern-roll 85, which revolve in the directions indicated by the arrows. These rolls 30 press the plastic composition firmly upon the zinc strip and impress it with a complement of the peripheral shape or configuration of the pattern-roll. In Fig. 1 the pattern-roll is 35 shown as cylindrical, so that the surface of the composition after being acted upon by it will be perfectly flat. From these rolls the zinc plate, with its coating of composition, passes between the sleeve 106 on stud 104 and the peripheries of cutters 110, which are held 40 down by springs 111 with sufficient force to cause them to cut through the composition to the zinc plate, leaving said composition in a number of strips adhering to the surface of 45 the single strip of zinc. From these cutters the strip of zinc, with its adherent strips of composition, passes over the stud 50, and is then removed from the machine. These strips of composition are then removed from the 50 zinc plate and used for coating moldings and other purposes. It will be seen that, instead of using a roller 85 of cylindrical form, a number of rollers such as the one shown in Fig. 5 or a single roller with two or more 55 patterns on its periphery might be secured on shaft 84, so as to impress two or more designs at a single operation upon a single broad strip of composition, which, after leaving the pattern-roll, would be cut by the knives 110 into 60 a number of separate strips of ornamented composition. The knives 110 are used only when a zinc or similar sheet is used. When it is not desired to use them, they are removed, together with the parts numbered from 105 to 65 109, inclusive, leaving stud 104 bare, as shown in Fig. 5. It will be understood that the guides 49 and 102 are adjusted so that the

strip to be operated upon fits snugly between them, and so that said strip will be guided and held in proper position with relation to the pattern-roll. If, instead of a zinc strip, the composition be laid on top of a strip of molding, the operation will be the same, except that the composition will not of course be removed from the molding after passing through the machine. Thus it will be seen the roll 41, the studs 48 and 50, and the sleeve 106 all assist directly in supporting the work, while nearly all of these parts are in turn supported by the yoke. Many features of the invention are not, however, limited to a work-support of this particular construction.

The work-support is made adjustable to various inclinations, in order that the surface of the molding against which the pattern-roll is to work may be placed substantially parallel with the working-surface of said roll, or, in other words, in order that the pressure shall be in a plane perpendicular to the surface against which it is exerted.

90 Referring to Fig. 5 it will be seen that with a horizontal work-support a pattern could not be impressed upon the part of the molding shown in the drawings, against which the pattern-roll is shown to be in contact.

95 I am aware that a machine has been constructed having a work-supporting roll capable of being oscillated, and I do not claim such a work-supporting roll, broadly, as my invention.

100 In order to incline the work-support, (the pattern-roll and its frame having been elevated and the frame 60, &c., slid to one side, if required,) the wheel 56 is turned so as to allow the jaws 52 and 53 to release the segment 51. The yoke 32 is then tilted upon its trunnions until the roll 41 comes to the desired inclination, after which jaws 52 and 53 are again tightened to hold it in place. The other parts are then adjusted to suit the requirements of the particular case.

105 For protecting portions of the molding that have been whitened or finished in some other way and which would be injured by contact with the roll 41, the latter may be provided with one or more rubber rings or bands 130, as shown in Fig. 11.

110 For ornamenting both sides of a strip, (a curtain-pole, for example,) a second pattern-roll may be substituted for the cylindrical roll 41.

115 My invention is not limited to the particular means shown in the drawings for preventing the yoke from oscillating upon its trunnions while the machine is at work, nor is it limited to the particular form of the yoke shown. The yoke might be modified by omitting all of the Y-shaped portion, thus reducing it in effect to a heavy shaft having at one end the bore for the shaft 35 and having the 120 boss 38, with the bore for the shaft 42. So far as I am aware I am the first to employ a tilting yoke of any construction for carrying the work-support.

Having thus described my invention, the following is what I claim as new therein:

1. The combination, with the roll 85, of the roll 41 and wheel 40, having coincident axes, a yoke by which said roll and wheel are carried, said yoke being capable of oscillation, and a power-wheel situated with its axis coincident with the axis of the oscillation of the yoke and gearing with wheel 40, substantially as set forth.
2. The combination, with the roll 85, of the roll 41, the shaft 39, by which it is carried, the yoke 32, having hollow boss 38, through which said shaft passes, and means for rotating said shaft, substantially as set forth.
3. The combination, with the roll 85, of the roll 41, having its inner end hollowed out, the shaft 39, the yoke having hollow boss 38, and means for rotating said shaft, substantially as set forth.
4. The combination, with the roll 85, of a work-support, a yoke capable of oscillation, by which said support is carried, a segment on said yoke, and means for locking and unlocking said segment at will, substantially as set forth.
5. The combination, with the roll 85, of a work-support, a yoke capable of oscillation, by which said support is carried, the segment 51 on said yoke, the clamping-jaws 52 53, between which said segment projects, and a hand-screw for operating said jaws, substantially as set forth.
6. The combination, with the roll 85, of roll 41, having one or more adjustable guides, each consisting of a ring formed in one piece, split, and provided on its two abutting ends with corresponding lugs for the reception of a clamp-screw, substantially as set forth.
7. The combination, with the roll 85, of a yoke capable of oscillation, means for securing said yoke in position, the roll 41, journaled to and carried by said yoke, and the stud 48, also carried by said yoke, substantially as set forth.
8. The combination, with the roll 85, of a yoke capable of oscillation, means for securing said yoke in position, the roll 41, journaled to and carried by said yoke, and the stud 48, also carried by said yoke and having the guide 49, substantially as set forth.
9. The combination, with the roll 85, of a yoke capable of oscillation, means for securing said yoke in position, the roll 41, journaled to and carried by said yoke, and the studs 48 and 50, also carried by said yoke and situated upon opposite sides of the work-supporting roll, substantially as set forth.
10. The combination, with the roll 85, the yoke, and the roll 41, of a work-supporting stud having an anti-friction sleeve or collar, substantially as set forth.
11. The combination, with the roll 85 and a work-support, of the stud 104, the shaft 108, a loosely connected thereto, the sleeve 109 on said shaft, and the cutters supported by said sleeve, substantially as set forth.
12. The combination, with the roll 85 and a work-support, of the stud 104, having arms 105, the links 107, the shaft 108, the sleeve 109 on said shaft, and the cutters 110, supported by said sleeve, substantially as set forth.
13. The combination, with the roll 85 and a frame resting upon the pedestal and carrying said roll, the gearing carried by said frame, the shaft 30, the pinion 88, having sliding connection with said shaft, and an arm extending from the movable frame and engaging said pinion for moving it longitudinally upon its shaft when said frame is moved, substantially as set forth.
14. The combination of the roll 85, the shaft 84, the vertically-movable frame carrying said shaft, the wheel 86 on said shaft, the wheel 87, 85 gearing therewith, the shaft 92, the lever 91, carrying said shaft, the shaft 30, about which said lever is movable, the pinion 88 on shaft 30, engaging wheel 87, and means for locking said lever in any desired position, substantially as set forth.
15. The combination, with a work-support, of roll 85, shaft 84, by which it is carried, the vertically-movable frame carrying said shaft, having flanges 74 and 75, the vertical guides 95 67 67^a, and means for elevating and lowering said frame, substantially as set forth.
16. The combination, with a work-support, of roll 85, shaft 84, by which it is carried, the vertically-movable frame having flanges 74 100 and 75, the vertical guides 67 and 67^a, the clamp-plate 76, the screw 77 78, and means for elevating and lowering the frame, substantially as set forth.
17. The combination, with the roll 85, of the stud 98, the arms 100, and the guides 102, carried by said arms, substantially as set forth.
18. The combination, with the roll 85, of the guides 102, the stud 98, by which they are supported, and the arm 97 and devices for adjustably securing it to the frame, substantially as set forth.
19. The combination, with the pedestal and an adjustable work-support, of a horizontally-movable frame resting upon the pedestal, and the roll 85, carried by said frame, substantially as set forth.
20. The combination, with the pedestal having rails 23, of the superposed movable frame having flanges 63 64 resting on said rails, and the roll 85, carried by said frame, substantially as set forth.
21. The combination, with an adjustable work-support, of the roll 85 and a shaft to which it is secured adjustable both vertically 125 and horizontally, substantially as set forth.
22. The combination, with an adjustable work-support and a pedestal, of a horizontally-movable frame resting upon said pedestal, a second frame adjustable vertically upon the first, and the roll 85, carried directly by the second frame, substantially as set forth.
23. The combination, with the roll 85, of an atomizer, a bracket for supporting it opposite

said roll, a pump, and a tube connecting said atomizer and pump, substantially as set forth.

24. The combination, with the roll 85 and an atomizer, of a jointed bracket supporting said atomizer, an air-compressor, and a tube connecting said atomizer and compressor, substantially as set forth.

25. The combination, with the roll 85, an atomizer, means for supporting it, an air-compressor, and a tube connecting said atomizer and compressor, of adjustable shields for regulating the escape of spray, substantially as set forth.

26. The combination, with the roll 85, the atomizer, means for supporting it, an air-compressor, and a tube connecting said atomizer and compressor, of the horizontally-adjust-

able shields 122 for regulating the width of the spray, substantially as set forth.

27. The combination, with the roll 85, the atomizer, means for supporting it, an air-compressor, and a tube connecting said atomizer and compressor, of the horizontally and vertically adjustable shields 122 and 124, substantially as set forth.

28. The combination, with the roll 85, of the jointed bracket 118, the cup 119, carried by said bracket, the bores 120 and 121, and means for forcing air through bore 120, substantially as set forth.

BERNIARD C. J. ANDERSON.
